UNITED STATES PATENT OFFICE.

THURMAN R. HUSTON, OF OMAHA, NEBRASKA.

MOP-WRINGER.

SPECIFICATION forming part of Letters Patent No. 730,125, dated June 2, 1903.

Application filed December 18, 1902. Serial No. 135,710. (No model.)

To all whom it may concern:

Be it known that I, THURMAN R. HUSTON, a citizen of the United States of America, residing at Omaha, in the county of Douglas and State of Nebraska, have invented certain new and useful Improvements in Mop-Wringers, of which the following is such a full, clear, and exact description as will enable others skilled in the art to which it appertains to make and use the same, reference being had to the accompanying drawings, forming a part hereof.

This invention relates to improvements in that class of mop-wringers which are attached permanently to a pail; and it consists in certain novel features hereinafter first fully described, and then particularly pointed out in the claim.

In the annexed drawings, which fully illustrate the invention, Figure 1 is a plan view of a mop-wringer in position within a pail. Fig. 2 is a view showing the wringer in elevation and the pail in section, and Fig. 3 is a similar view showing the wringer-rolls adjusted to wring a mop.

The pail A is of the usual or any preferred form and is provided with the feet B, common in devices of this class.

The wringer-frame C consists of a bar bent into substantially U shape and having short lips D at its ends, through which fastening-screws are inserted into the pail. Additional fastening-screws are inserted through the angles of the frame into the pail, so that the frame is rigidly secured within the pail just below or at the upper edge of the same. The parallel supporting side arms of the frame are provided with notches E in their lower edges near their centers, and between said notches and the cross-bar or shoulder of the frame longitudinal slots F are formed in the said side bars. Arranged between the side bars is a wringer-roll G, which is supported by headed studs or trunnions H, projecting from its ends through the slots F and adapted to slide in said slots. The studs and the roller carried thereby are normally forced toward the inner ends of the slots by springs I, having their ends engaged over the studs or trunnions and depending a short distance therefrom to a point where they are formed into coils J, from which they are carried upward to the side bars and engaged in open-

ings or perforations near the outer ends of the same, as shown at K. Between the side bars is arranged a swinging U-shaped frame L, which is pivoted to the said side bars near the ends of the same and depends below the same. A wringer-roll M is mounted between and carried by the lower ends of this frame, and its trunnions N project beyond the frame, so that when the roller is swung upward to its operative position the trunnions will impinge against the supporting-frame, and thereby limit the said upward movement. The trunnions enter the notches E in the supporting-frame, so that the roller is permitted to swing upward into the same horizontal plane as the spring-pressed roller G, and thereby secure the greatest possible efficiency of the device. Secured to the wringer-roll-carrying frame is a lever arm or handle O, which is attached to the upper cross-bar or shoulder of the frame and projects therefrom at approximately a right angle, departing from such an angle only enough to cause it to project above, so as to be easily grasped when the roll is in its lowest position.

The construction and arrangement of the several parts being thus made known, it is thought the operation of the device will be readily understood and appreciated. The pail is partially filled with water, to which may be added soap or other cleaning agents, and the mop is dropped between the rolls, the normal position of which is shown in Fig. 2. The lever or handle O is then grasped and swung upward and outward, so that the frame to which it is attached and the roll carried by that frame will be swung upward and inward toward the spring-pressed roll, the mop being compressed between the two rolls. The rolls are held thus together while the mop is being drawn from the pail, and the pressure exerted thereby effectually squeezes the surplus water from the mop. When the mop has been withdrawn, the weight of the frame and the roller causes it to automatically return to its initial position. It will be observed that the lever-arm or handle is at one side of the roll-carrying frame, so that it will not interfere with the movement of the mop into or from the pail and also that it may be more easily reached by the operator than if it were at the center of the frame. The spring-pressed roll auto-

- matically yields to knots or other unevennesses in the mop, while it at the same time exerts a constant pressure thereon. The supporting-frame does not take up any needed space within the pail and supports the device rigidly in position, while the notches in the lower edges of the same permit the swinging roll to be brought into the same horizontal plane as the spring-pressed roll, in which position the distance between the centers of the rolls will be reduced to a minimum, and consequently the pressure exerted by the rolls on the mop will be at the maximum.
- The device is extremely simple in its construction and is capable of being manufactured very cheaply.
- Having thus described my invention, what I claim, and desire to secure by Letters Patent, is—
- 20 The improved mop-wringer herein described and shown consisting of a supporting-frame

adapted to be secured within a pail and having notches in the lower edges of its side bars, a wringer-roll mounted in said frame, a spring secured to the said frame and holding the said roll normally toward the center of the frame, a wringer-roll-carrying frame pivotally hung in the supporting-frame at the end opposite the spring-pressed roll, a lever projecting from the said frame, and a wringer-roll mounted in and between the lower ends of said frame and having its trunnions extended beyond the said frame and adapted to engage the notches in the side bars of the supporting-frame.

In testimony whereof I have signed this specification in the presence of two subscribing witnesses.

THURMAN R. HUSTON.
